UNITED STATES PATENT OFFICE

151,910

DESIGN FOR A RIDING STICK TOY

Adrien R. Mellor, Loma Linda, Calif.

Application June 11, 1947, Serial No. 139,583

Term of patent 7 years

(Cl. D34—15)

To all whom it may concern:

Be it known that I, Adrien R. Mellor, a citizen of the United States, residing at Loma Linda, in the county of San Bernardino and State of California, have invented a new, original, and ornamental Design for a Riding Stick Toy, of which the following is a specification, reference being had to the accompanying drawing, forming part thereof.

Figure 1 is a side elevational view of a riding stick toy, showing my new design,

Figure 2 is a top plan view, taken in the direction of the arrow 2 in Figure 1, and

Figure 3 is a front elevational view, taken in the direction of the arrow 3 in Figure 1.

I claim:

The ornamental design for a riding stick toy, as shown.

ADRIEN R. MELLOR.
